United States Patent Office.

VENTILATING FAN FOR GAS-BURNERS.

HENRY SEHER, OF ST. LOUIS, MISSOURI.

Letters Patent No. 60,566, dated December 18, 1866.

The Schedule referred to in these Letters Patent and making part of the same.

TO ALL WHOM IT MAY CONCERN:

Be it known that I, HENRY SEHER, of the city and county of St. Louis, in the State of Missouri, have invented a new and improved Mode of Ventilating Rooms; and I do hereby declare that the following is a full and exact description thereof, reference being had to the accompanying drawing, and to the letters of reference marked thereon, like parts being designated by like letters in the several figures.

The nature of my invention consists in constructing a wheel having inclined and radial fans, buckets, or wings, their surfaces being nearly parallel with each other, and having openings between them; said wheel having a central hub, and turning or revolving on a supporting bracket, turned or propelled by heated air ascending from the flame of a lamp, lighted gas, or similar flame.

To enable others skilled in the art to make and use my invention, I will proceed to describe its construction and operation. In the drawings—

Figure 1 represents a top or plan view of my ventilating machine.

Figure 2, an elevation of same, showing how supported and attached to a gas pipe.

Figure 3 is a section of central hub.

A represents the radial wings, fans, or buckets, secured in any suitable way to a central ring, B, so that they can be easily put in place or removed, or the angle of inclination be varied. There are openings or air-spaces between these radial buckets, which, however, overlap each other. The ring, B, is connected by several radial strips, b, to a central hub, C, which has a central hole or opening, c, in its lower end, and in which a supporting bracket, D, is placed, and on which the wheel, A, revolves. This bracket again has its suitable support; as shown, is held by a compound clamp, E, which hugs a vertical gas-pipe F. These adaptations are varied by circumstances, being a mere matter of mechanical fitting and convenience.

The operation is simply as follows: Taking, for example, a vertical gas-pipe, pendent or dropping from the ceiling, and having a horizontal arm, on which there is a burner, the clamp E is first secured to pipe F (hugging it) by means of two screws, p, and say a foot, more or less, above the horizontal arm referred to. The lower end, f, of bracket D is held by this clamp, E. The hub of wheel A is now placed on the other or top end, s, of the bracket, which enters the lower hole, c, and passing upward goes into a central hole, d, of an upper plate, e; just above this plate, e, there is a glass plate, f, which is held in place by another plate or disk, g, above it, which is secured to the top of the hub, holding e and f in place. This arrangement, say, brings the wheel A some two feet, more or less, above and directly over the flame of lighted gas at the end of horizontal arm. A heated column of air ascends from the flame, which has more or less motion and force. This heated air impinges against the inclined under sides of the radial wings or buckets and passes on up between them, at same time generating a revolution of the wheel, which acts as a fan, mixing or disturbing, more or less, the atmosphere of a room, producing a current, acting as a ventilator, and assisting in driving out impure air, if there be any egress for it. Another advantage is the following: that the under side of the wheel will catch most of the products of combustion and retain them, thus preventing to a great extent any soiling of the ceiling above. The wheel can be removed at any time very easily; be cleaned; if of metal, brightened or polished; and it will serve as a reflector when revolving. The under side of wings may have a covering of looking or other glass for such purpose. I prefer constructing my machine of metal. However, different materials may be used, separately or in combination. The object of glass plate f, (it being the bearing of wheel A on bracket D,) is to avoid friction and lead to a more rapid revolution of the wheel, thus increasing its utility.

I am aware many wheels have been constructed to be driven by water, steam, and even wind, the latter commonly called windmills. I am also aware of the "flutter" wheels, usually placed in windows for ventilating purposes; but these I do not claim. It will be seen that mine is differently constructed, applied, and operated than any others heretofore known. The buckets of my wheel are easily put in or taken out, cleaned, and their angle changed, as well as their purposes multiplied or increased, as set forth; so that the wheel, as constructed, supported, and applied, is novel as well as useful.

Having thus described my invention, what I claim as new, and desire to secure by Letters Patent of the United States, is—

A ventilating wheel, constructed, operated, and applied in the manner as shown and described, and for the purpose set forth.

HENRY SEHER.
